(57) **CLAIM**

The ornamental design for a belt-securable pocket for personal electronic alarm, as shown and described.

DESCRIPTION

FIG. 1 is a front perspective view showing my new design.

FIG. 2 is a back perspective view thereof.

FIG. 3 is a front elevational view thereof.

FIG. 4 is a side elevational view thereof.

FIG. 5 is a rear elevational view thereof.

FIG. 6 is a top plan view thereof.

FIG. 7 is a bottom plan view thereof.

FIG. 8 is a front elevational view showing a cover strap of my new design in a released position.

FIG. 9 is a side elevational view thereof.

FIG. 10 is a rear elevational view thereof.

FIG. 11 is a top plan view thereof; and,

FIG. 12 is a bottom plan view thereof.

The broken lines shown in the drawings are optional sewing hem lines for illustrative purposes only and form no part of the claimed design.
